UNITED STATES PATENT OFFICE.

ALBERT R. TEARE, OF LAKEWOOD, OHIO, ASSIGNOR TO JAMES C. MILES, OF CLEVELAND, OHIO.

HEATING AND VENTILATING APPARATUS.

Application filed January 23, 1928. Serial No. 248,627.

This invention relates to heating and ventilating apparatus, particularly that which is intended for use in connection with the operation of a hot air heating furnace. In order to insure positive and uniform distribution of air from the furnace through the various delivery pipes and into the rooms to be heated, it is advantageous to utilize a fan which is placed at or near the inlet to the 10 heating chamber of the furnace and to operate the fan at certain intervals. Ordinarily a certain area of inlet opening is required to maintain an adequate volume of air through the heating chamber under the gravity system. Accordingly, if a fan is placed in the opening, provision must be made for enclosing the space between the fan and the walls of the inlet conduit so as to insure passage of air through the heating chamber 15 when the fan is in operation. On the other hand, provision must be made for opening the damper when the fan is stopped so as to maintain the necessary flow of air through the heating chamber. Unless provision is 20 made for the free passage of air when the fan is stopped, the furnace will be quickly burned out.

The principal object of the present invention is to provide an apparatus which includes a fan and damper which is placed adjacent the inlet to the heating chamber of a hot air furnace and is so arranged that the fan cannot be started until the damper is moved to closed position, and cannot be 25 opened until the current to the fan motor is shut off. When the fan is so stopped, the damper will then be automatically moved to open position.

In the drawings, Fig. 1 shows a part of a 30 hot air furnace with an inlet conduit leading thereto, and having my invention mounted therein; Fig. 2 is a vertical transverse section taken through the inlet conduit on a plane indicated by the line 2-2 in Fig. 1; Fig. 3 is a horizontal section taken through the apparatus on a plane indicated by the line 3-3 in Fig. 2; Fig. 4 is a diagrammatic view showing the relative position of the switch and damper arm when the fan is off; 35 and Fig. 5 is a similar view illustrating the relative position of these parts when the fan is on.

For convenience of illustration, 40 indicates part of a heating chamber of a hot air furnace, while 11 indicates a conduit through

which air may be led into the heating chamber. Within the conduit I have shown a frame 12 which is in the nature of a partition extending across the conduit in a substantially vertical plane. The frame is illustrated as having a fan opening 13 and damper openings 14. A motor driven fan 15 is illustrated as being mounted adjacent the fan opening while dampers 16 are illustrated as being mounted in the damper openings. While I have illustrated the frame as having two damper openings, it is obvious that one opening would be sufficiently adequate for purposes of my invention.

The dampers are arranged to be pivotally mounted upon a horizontal shaft 20, which may be supported entirely by the frame, although I have illustrated it as extending through one wall of the conduit as at 21, and through the opposite wall as at 22. The dampers are rigidly mounted on the shaft and the shaft is arranged to be rotated, preferably by means outside the conduit. One form of apparatus for accomplishing this is shown as an arm 25 which is rigidly fastened to the shaft at a point outside the conduit, and is provided with a counterweight 26 for normally holding the arm in upright position. At such time the dampers 16 are maintained in open position as indicated by the broken lines in Fig. 4. The closed position of the arm and dampers is indicated in Fig. 5.

To prevent the fan from being started until the damper is closed, a switch 30 for controlling the motor 31 is shown as being mounted on the outer side of the conduit while an arcuate arm 32 is illustrated as being carried by the arm 25 and as being interposed in the path of movement of the switch arm 33. Thus, the arm 32 prevents the switch arm from being moved to closed position so long as the dampers are open. Hence, it is necessary to manually close the dampers by moving the arm 25 to the position shown in Fig. 5. This movement causes the arm 32 to be moved out of the path of the switch arm, and thus permits the operator to close the switch.

When the switch is closed, the end of the arm 32 is in engagement with one of the bars of the switch arm, wherefore the counterweight 26 cannot return the dampers to open position until the switch is opened. The end of the arm 32 is suitably electri-

cally insulated from the switch as indicated at 35. When the switch arm is moved to the open position, the counterweight automatically opens the damper as soon as the switch arm 33 clears the end of the damper arm.

The wiring diagrams illustrated in Figs. 4 and 5 indicate a source of current supply at 40 with suitable leads which pass through the switch and are connected to the motor. With this arrangement, the fan cannot be started until the damper is closed, and the fan cannot be stopped without the damper being open. To this end, the counterweight is especially heavy to insure positive opening of the damper as soon as the fan is stopped. Thus, there is a manual closing of the damper when the fan is started, and an automatic opening of the same when the fan is stopped. Accordingly, the danger of the damper remaining closed when the fan is shut off is eliminated, and an adequate circulation of air is thereby provided so as to prevent the furnace from burning out.

Having thus described my invention, I claim:

1. The combination of a heating chamber having an air inlet thereto, a fan and a damper associated with the inlet, an electric motor for operating the fan, a switch in the motor circuit, a member for actuating the damper, and means for preventing closing of the switch until the member is moved a predetermined amount in one direction.
2. In combination, with the heating chamber of a hot air furnace having an air inlet thereto, of a fan, a damper associated with the inlet, the damper being arranged to be closed when the fan is in operation and to be opened when the fan is stopped, an electric motor for operating the fan, a switch in circuit with the motor, and means associated with the switch for preventing the damper from being opened until the switch is opened.
3. In combination, an air conduit, a fan and a damper associated with the conduit, an electric motor for operating the fan, a

circuit controller therefor, means for operating the damper, said means being rendered inoperative for moving the damper when 50 said controller is in closed position.

4. In combination, a hot air conduit, a fan and a damper associated with the conduit, an electric motor for operating the fan, a circuit controller therefor, means for operating the damper, said means being rendered inoperative for moving the damper when said controller is in closed position, and said means being automatically rendered operable when the controller is moved to open 60 position.

5. The combination with an air conduit, of a fan and a damper mounted within the conduit, an electric motor for operating the fan, a controller in circuit with the motor and mounted outside the conduit, an arm for operating the damper, and means coacting between the controller and arm for preventing the controller from being moved to closed position until the damper is closed, said 70 means also acting to prevent opening of the damper until the controller is moved to open position.

6. The combination with the heating chamber of a hot air furnace having an air inlet 75 conduit leading thereto, of a fan and a damper mounted within the conduit, an electric motor for operating the fan, a controller in the motor circuit, said controller being mounted outside the conduit and on one of 80 the walls thereof, the damper being arranged to be swung about a pivot, there being an arm mounted outside the conduit and arranged to be turned with the damper, said arm having a portion thereof interposed in the path 85 of movement of a controller and functioning to prevent the controller from being closed so long as the damper is open, and said controller functioning to prevent opening of the damper so long as the controller is closed. 90

In testimony whereof, I hereunto affix my signature.

ALBERT R. TEARE.
